United States Patent Office

Des. 210,820
Patented Apr. 23, 1968

210,820

BUILDING

Ralph Robert Knapp, Evansville, Ind., assignor, by mesne assignments, to Burger Farms of America, Inc., Evansville, Ind., a corporation of Indiana

Filed Oct. 7, 1966, Ser. No. 4,193

Term of patent 14 years

(Cl. D13—1)

FIG. 1

Des. 210,820

PAGE 2

FIG. 2

FIG. 4

FIG. 1 is a front view of a building showing my new design;

FIG. 2 is a view in elevation of a side of the building of FIG. 1, looking from left to right in FIG. 1;

FIG. 3 is a view in elevation of another side of the building of FIG. 1, looking from right to left in FIG. 1; and,

FIG. 4 is a view in elevation of the back of the building of FIG. 1.

I claim:

The ornamental design for a building, as shown.
